EVAPORATING APPARATUS

Ralph J. Serpas, Minneapolis, Minn.

Application August 6, 1934, Serial No. 738,646

5 Claims. (Cl. 159—23)

This invention relates to evaporators and evaporating processes for use particularly in pulp mills, sugar mills, milk drying apparatus, chemical apparatus etc., although capable of use in evaporating all manners of liquids.

It is the general object of the invention to provide a novel and improved evaporator and a novel and improved evaporating process, which will operate with great economy and efficiency in evaporating liquids of all kinds.

The objects and advantages of the invention will more fully appear from the following description, made in connection with the accompanying drawing, wherein like reference characters refer to the same or similar parts throughout the various views, and, in which,

Fig. 1 is a more or less diagrammatic view in side elevation illustrating an embodiment of my evaporating apparatus, the tank of the apparatus being shown in vertical section; and

Fig. 2 is a detail in enlarged scale showing in vertical section certain of the parts.

In accordance with the invention, there is provided a large tank 3 preferably made in sections, each section being equipped with one or more doors 4, so that ready access may be had to the interior of the tank as occasion demands. In the lower portion of the tank there is provided a steam chest 5, the portion of the tank below the steam chest forming a chamber 6. Open ended tubes 7 run upwardly through the steam chest 5 and they communicate at their lower ends with the chamber 6 and they communicate at their upper ends with the space in the tank immediately above the chest. Above the steam chest 5 a plurality of horizontal liquor holding trays 8 and 9 are provided in the tank 3. The trays 8 and 9 are disposed in spaced superimposed relation, the trays 9 being alternated relative to the trays 8 from the upper part of the tank downwardly. The trays 8 are secured to the tank 3 by means of brackets 10 and the peripheral edges of the trays 8 are centrally spaced from the walls of the tank to form passages 11 between these edges and the walls of the tank. The peripheral edges of the trays 8 are provided with upstanding flanges of short length. The trays 9 have their peripheral edges attached to the side walls of the tank 3 and in the form shown these trays are provided with central openings forming passages 12. The edges of the trays 9 adjacent the passages 12 are provided with upstanding flanges of the same height as the flanges of the trays 8.

Mounted in openings in the bottoms of the various trays 8 and 9 are a multiplicity of short

open ended tubes 13, best shown in Fig. 2. These tubes extend upwardly from the bottoms of the trays to points spaced somewhat below the upper edges of the flanges of the trays to which the tubes are secured. Caps 14 of inverted cup-shape extend over the upper ends of the tubes 13 and these caps are of considerably greater diameter than the tubes 13 and they may be conveniently attached to the tubes by means of apertured collars 15 attached to the tops of the caps, projecting downwardly therefrom and having lower portions embracing the upper portions of the tubes 13. The collars 15 are each provided with one or more inturned lugs 15a which overlie the upper edge of the tube 13 to which the particular collar is attached. The top of each cap 14 is spaced above the level of the upper end of its tube 13 and a small aperture 14a is formed in the top of the cap immediately above the tube.

A liquor supply pipe 16 is mounted in the upper portion of the tank 3 and it has a discharge mouth 16a located above the uppermost tray 8 to discharge thereto. Connected to the pipe 16 is a pipe 17 equipped with a valve 18 and connected to the discharge outlet of a pump 19, this pump being driven by any suitable source of power (not illustrated). There is provided a large storage tank 20 within which the liquor to be evaporated may be held. A pipe 21 mounted in the bottom of the tank 20 and equipped with a valve 22 runs downwardly from the tank and is connected to a pipe 23 which, in turn, is connected to the inlet port of pump 19. A branch pipe 24 equipped with a valve 25 is connected at its lower end to pipe 21 above the valve 22 and it is connected to pipe 16 at its upper end. A pipe 26 equipped with a valve 27, is connected to pipe 17 between the discharge outlet of pump 19 and valve 18 and this pipe 26 discharges into a rotary drier 28.

The pipe 23 is connected at one end to the lower part of the tank 3 to communicate with the chamber 6 and it runs directly to the inlet port of the pump 19, the pipe being provided with a valve 29. An inverted U-shaped pipe 30 has one small arm 30a connected to the pipe 23 ahead of the valve 29 and another large arm 30b connected to the pipe 23 between the valve 29 and the pump 19. The arm 30a is equipped with a valve 31. The U-shaped pipe 30 projects upwardly to a point above the level of the steam chest 5 in tank 3, i. e. to the level that it is desired to maintain liquor in the tank 3, and there is connected to the upper portion of the pipe 30, between the arms thereof, an upwardly projecting pipe 32 open at 55

its upper end to the atmosphere and equipped with a valve 52. Between the valve 31 and the pipe 32 there is provided a back flow check valve 33 in the U-pipe 30.

5 A drain pipe 34 equipped with a valve 35 is connected to the bottom of the tank 3. A flanged vapor outlet port 36 is provided in the top of the tank 3 and connected at one end to this outlet port is a tube 37 for carrying off the vapor from the tank. This tube 37 runs into a condenser 38 or to a vacuum pump, (not illustrated). The condenser 38 is not shown in detail, but it may be provided with a pipe 39 for carrying off the condensed liquor.

10 15 It is desirable at times to drain all the various trays 8 and 9 and for this purpose the various trays are provided with vertical aligned apertures through which a rod 40 extends. The walls of the trays about the apertures form valve seats 20 with which valves 41 mounted on rod 40 cooperate. The upper portion of the rod 40 extends through a packing gland 42 in the top of the tank 3 and is pivotally connected to a lever 43 fulcrumed on a bracket 44 attached to the top of 25 the tank 3. By operation of the lever 43, it will be seen that all the various valves 41 may be simultaneously raised from their seats to permit drainage of whatever liquor may be held within the trays 8 and 9.

30 35 A water glass 45 for determining the liquid level within the tank 3 is connected at its lower end to the tank below the steam chest 5 and is connected at its upper end to the tank in spaced relation above the top of the steam chest. A steam supply pipe 46 equipped with a valve 47 supplies steam to the chest 5 and a pipe 48 equipped with a valve 49 is connected to the lower part of the steam chest and will carry off condensed steam (water), and cooled steam from 40 the chest. A steam pressure gauge 50 is connected to the pipe 46, while another pressure gauge 51 adapted to register the lack of pressure or vacuum in tank 3 is connected to the tank preferably at about the position shown.

45 Operation

When it is desired to evaporate liquor contained in the tank 20, it is first necessary to pump the requisite amount of liquor into the tank 3. 50 Steam will be supplied to the steam chest 5 through the supply pipe 46 controlled by valve 47 and condensed water and some steam will be discharged from the steam chest through the discharge pipe 48 controlled by valve 49. By 55 observation of the gauge 50 and manipulation of the two valves 47 and 49 the pressure of steam within the chest may be regulated. Valves 35, 29, 31, 52, 27 and 25 will be closed and valves 22 and 18 will be opened and the pump 19 will be placed 60 in operation. The pump 19 will then draw liquor from the tank 20 through pipe 21 and the right hand part of pipe 23 into the pump and force this liquor upwardly through pipe 17 and pipe 16 to discharge through the mouth 16a into 65 tank 3 above the uppermost tray 8. The liquor discharged from the mouth 16a will first drop into the uppermost tray 8 and accumulate there until the level of liquor within the tray rises above the upper ends of the tubes 13 mounted in 70 this tray. The liquor will then overflow into the numerous tubes 13 and will drop downwardly through the tubes in small drops or fine streams to the uppermost tray 9 below the tray 8. It will, of course, pass through the air within the tank 75 3 between the two uppermost trays 8 and 9 in

5 finely divided form. Similarly, the liquor will accumulate in the uppermost tray 9 until its level within this tray rises above the level of the upper ends of the tubes 13 mounted on the tray 9 and the liquor will then overflow into the tubes 13 10 on the uppermost tray 9 and pass on downwardly in finely divided form through the air in the tank 3 to the next lower tray 8. In this manner all the trays 8 and 9 will be filled until the liquor overflows from the lowermost tray 9. The liquor will then first fill the chamber 6 and then fill the tubes 7 through the steam chest 5 until the level of liquid, as determined by examination of the water glass 45, reaches about the point shown or to approximately the level of the upper part 15 of the U-pipe 30.

15 In connection with the action of the tubes 13 in transmitting the liquor from one tray to another, it should be noted that before the liquor level in any tray reaches a point above the upper ends of the tubes 13 mounted in that tray, the lower edges or skirts of the caps 14 will be immersed in the liquor so that the upper ends of the tubes 13 will be sealed from the free passage of air or vapor upwardly from below the tray 20 through these tubes. The apertures 14a are provided in the caps 14 to prevent siphoning action 25 when the liquor first starts to overflow the upper ends of the tubes 13. After the trays 8 and 9 are once filled, the level of liquor in these trays 30 will be maintained automatically.

35 After the tank 3 has been filled with liquor, as described, the valve 22 will be closed and valve 29 will be opened. The liquor in the tank 3 will now be recirculated from the bottom of the tank to the top of the tank. The pump 19 will draw liquor from chamber 6 through pipe 23 and will force the same through pipe 17 and pipe 16 to discharge from the mouth 16a. Finely divided particles of liquor will thus continuously 40 drop from higher trays 8 or 9 in the tank 3 to lower trays 9 or 8. The steam chest 5 in the lower part of the tank will heat up the liquor in the tubes 7 and above and below the steam chest. This liquor will begin to vaporize through 45 boiling action and vapor rising from the body of liquor in the lower part of the tank will pass upwardly in a tortuous path between, through and about the various trays 9 and 10. The vapor below the lowermost tray 9 will pass upwardly through the passage 12 in this tray after imparting some of its heat to the bottom of the tray. The vapor then will strike the bottom of the lowest tray 8 and move laterally toward the walls of the tank 3 and pass on upwardly through the passages 11 between the lowermost tray 8 and the side walls of the tank. Then the vapor will pass through the passage 12 in the next higher tray 9 and so on until it reaches the top of the tank 3. During its travel upwardly, the 50 vapor not only heats the various trays 8 and 9 to impart heat to the liquor contained in these trays, but it also comes into intimate contact with the fine particles of liquor dropping downwardly from one tray to another and heats the 55 liquor in this manner. Accordingly, the liquor contained in the various trays 8 and 9 becomes highly heated and the liquor dropping down from the lowermost tray 9 to a point above the steam chest 5 is highly heated so as to readily 60 vaporize. The vapor passing upwardly through the drum must follow the tortuous path indicated by the arrows in Fig. 1, as it cannot readily pass upwardly through the various tubes 13 due to the liquid seals over the upper ends of these 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

tubes formed by the caps 14, the skirts of which are immersed in the liquor held within the trays.

The vapor rising to the top of the tank 3 passes out through the tube 37 into the condenser 38 or equivalent vacuum pump. If the condenser 38 is used, the vapor will be condensed into liquid form and drawn off through the pipe 39 and this action will create a partial vacuum in the tube 37 and in the tank 3 to assist in carrying off the vapor and to reduce the necessary temperature required for vaporization of the liquor. As the quantity of liquor in the tank is depleted through vaporization of the water in the liquor, additional quantities of fresh liquor from the tank 20 may be introduced into the tank 3 by partially opening the valve 25. Some liquor will then be drawn through pipe 24 from the bottom of the tank to be introduced with the main body of liquor recirculated through the pipe 16 into the tank.

When the liquor has been sufficiently concentrated in tank 3, the valve 18 may be closed and valve 27 opened whereupon the pump 19 will draw off the liquor from the chamber 6 through pipe 23 and force this liquor through the lower part of pipe 17 and pipe 28 into the rotary drier 29 or elsewhere.

It is highly desirable in certain uses that after the evaporator has been once set in full operation and the liquor therein has been brought to the proper concentration, that a certain quantity of the concentrated liquor be constantly drained off from the tank 3 and that a certain quantity of fresh or unevaporated liquor be constantly supplied to the tank 3, so as to maintain the concentration of liquor drawn off the same. This can be readily done with the present apparatus. The valve 29 and valve 22 will be closed and valves 31 and 32 will be opened. Valve 18 will be partially closed, valve 27 partially closed and valve 25 partially closed. When the level of liquor in the lower part of the tank 3 rises to a point above the top of the U-pipe 30, liquor will flow by gravity from the tank 3 through the left portion of pipe 23, arm 30a and the upper part of the U-pipe 30 into the large arm 30b. A siphon action through the U-pipe will not take place due to the fact that the pipe 32, when the valve 32 is open, is open at its upper end to the atmosphere. Back flow of air to the tank 3 through the arm 30a of the U-pipe is prevented by reason of the back flow check valve 33. The level of liquor in the lower part of the tank 3 will be maintained by the U-pipe 30 at approximately the point indicated in the drawing. The pump 19 will draw off the liquor in the arm 30b through the pipe 23 and the pump will force some of this liquor, which it should be stated is highly concentrated, through the pipe 26 to the rotary drier 29, the setting of the valves 27 and 18 determining what quantity of this liquor will be carried off to the drier, and what quantity will be recirculated to the tank 3. The pump 19 will force a portion of the liquor through the pipe 17 and pipe 16 into the tank 3 and along with this recirculated and concentrated liquor a quantity of undehydrated liquor will pass over to the tank 3 from the tank 20 by passage through the pipe 24 and pipe 16. The quantity of undehydrated liquor admitted will be determined by the setting of the valve 25. By proper adjustment of the three valves 27, 18 and 25, the apparatus can be kept in continuous operation so that a definite quantity of highly concentrated liquor can be drawn off to the

drier 28, a definite quantity of fresh liquor may be fed to the tank 3, the liquor level in the bottom of the tank 3 may be maintained substantially constant at a point approximately level with the upper part of U-pipe 30 for most efficient evaporating action and the liquor drawn off will have a relatively constant degree of concentration.

Easy access to various parts of the tank 3 may be had through the various doors 4. When it is desired to clean out the tank 3, the left end of lever 43 may be depressed to raise the various valves 41 from their seats and the liquor in the various trays 89 will then drain to the bottom of the tank 3. By opening the valve 35, the entire tank may be emptied.

It will, of course, be appreciated that the various trays 8 and 9 may be differently constructed and arranged for causing a tortuous circulation of the vapor through, about and around these various trays. It will also be understood that in place of the tubes 13 and caps 14, other means having the equivalent function of the tubes and caps may be provided.

It will be seen that a most efficient and economical evaporating apparatus and evaporating process has been provided. The heat of the vaporized liquor is utilized for preheating the liquor before it is carried to a point about the steam chest 5. The entire evaporating process may be carried out with the simple apparatus shown without requiring evaporation by several stages as is customary.

It will, of course, be understood that various changes may be made in the form, details, arrangement and proportions of the various parts of my apparatus and that various changes may be made in the steps of my evaporating processes without departure from the scope of the present invention, which, generally stated, consists in the matter shown and described and set forth in the appended claims.

What is claimed is:—

1. An evaporator having in combination, a tank, means for supplying the liquor to be evaporated at the upper part of the tank, heating means in the lower part of the tank, means for withdrawing vapor from the upper part of the tank, a plurality of trays mounted in superposed spaced relation in the tank above said heating means, said trays being constructed and arranged to permit of a tortuous circulation of vapor upwardly from the lower part of the tank through and about said trays, a multiplicity of short tubes carried by each tray and projecting therethrough, said tubes having open upper ends spaced above the bottoms of the trays in which they are mounted, downwardly flanged caps attached to the upper ends of said tubes and sealing by liquid the passage of vapor upwardly through the same while permitting the overflow of liquor from said trays through said tubes, the uppermost trays receiving from said supply means and the liquor overflowing through said tubes passing in finely divided state from upper trays to lower trays.

2. An evaporator having in combination, a tank, a steam chest in the lower part of the tank, said tank forming a liquor containing chamber below said steam chest, open ended tubes running upwardly from said chamber through said steam chest, a plurality of trays mounted in superposed relation in said tank above said steam chest, there being vapor passages through said trays permitting a tortuous travel of vapor upwardly through

and about said trays, a multiplicity of small conduits mounted in each tray and having admission openings spaced above the bottom of the tray, means sealing said admission openings to prevent the passage of vapor upwardly through said conduits while permitting the overflow of liquor from said trays through said conduits, means for withdrawing liquor from said chamber, means for supplying liquor to said tank, above the uppermost tray and means for withdrawing vapor from said tank above the level of the uppermost tray.

3. An evaporator having in combination, a tank, heating means in the lower part of said tank, means for supplying liquor to be evaporated at the upper part of the tank, means for drawing off vapor from the upper part of the tank, a plurality of trays mounted in superposed spaced relation in the tank above said heating means, said trays being constructed and arranged to permit of a tortuous circulation of vapor upwardly from the lower part of the tank through and about said trays, a multiplicity of small overflow conduits mounted in and extending through the respective trays and having admission openings located above the levels of the bottoms of the respective trays in which they are mounted, the uppermost tray receiving from said supply means and the liquor overflowing through said conduits, passing from upper trays to lower trays, liquid seals for the admission openings in said

conduits permitting the passage of liquor from said trays to said admission openings but preventing the passage of vapor upwardly through said conduits, and means for drawing off liquor from the lower part of said tank.

4. An evaporator having in combination, a tank, heating means in the lower portion of said tank, a portion of said tank below said heating means comprising a liquor containing chamber, a plurality of trays mounted in superposed relation in said tank above said heating means, there being vapor passages through said trays permitting a tortuous travel of vapor upwardly through and about said trays, a multiplicity of small conduits mounted in each tray and having admission openings spaced above the bottom of the tray, means sealing said admission openings to prevent the passage of vapor upwardly through said conduits while permitting the overflow of liquor from said trays through said conduits, means for exit of liquor from said chamber, means for supplying liquor to said tank above the uppermost tray and means of exit for vapor from said tank above the level of the uppermost tray.

5. The structure defined in claim 4 and the uppermost portion of each of said conduits being provided with a restricted relief vent to prevent siphon action in said conduits.

RALPH J. SERPAS. 30
